UNITED STATES PATENT OFFICE.

ALVIN J. MUSSELMAN, OF CHICAGO, ILLINOIS, ASSIGNOR TO INDIANA RUBBER & INSULATED WIRE CO., OF JONESBORO, INDIANA, A CORPORATION OF INDIANA.

DESIGN FOR A VEHICLE-TIRE.

52,224.

Specification for Design.

Patented July 23, 1918.

Application filed April 27, 1918. Serial No. 231,262. Term of patent 7 years.

To all whom it may concern:

Be it known that I, ALVIN J. MUSSELMAN, a citizen of the United States, residing in the city of Chicago, in the county of Cook and State of Illinois, have invented a new, original, and ornamental Design for Vehicle-Tires, of which the following is a specification, reference being had to the accompanying drawing, forming a part thereof, wherein—

The figure represents a perspective view of the tire showing the embodiment of the design.

My design is applied to a pneumatic ve-

hicle tire and consists of five circumferential bands, a center raised circumferential band provided with raised diagonal strips thereon, two circumferential bands provided with raised star designs and two circumferential bands of contrasting color.

The said design is impressed and painted upon the outer surface of pneumatic tire shoes or of single tube tires.

What I claim and desire to secure by Letters Patent is:

The ornamental design for a vehicle tire substantially as shown.

ALVIN J. MUSSELMAN.
